HYDRAULIC SAFETY DEVICE FOR POWER PRESSES AND THE LIKE

Filed July 5, 1929

UNITED STATES PATENT OFFICE

HENRY PELS, OF BERLIN-CHARLOTTENBURG, GERMANY

HYDRAULIC SAFETY DEVICE FOR POWER PRESSES AND THE LIKE

Application filed July 5, 1929, Serial No. 376,261, and in Germany September 4, 1928.

This invention relates to a hydraulic safety device for power presses and similar machines to compensate for excessive resistance offered to the working stroke of the tool carrier. The safety device is intended to protect the machine when the highest permissible pressure on the tool carrier is exceeded. Such safety devices hitherto have been provided with two valves, namely a suction-valve and a compression valve which, if the flow of the hydraulic medium is too great, owing to high speed of the piston, easily become damaged and leaky.

According to the present invention only one valve is employed to control the flow of the hydraulic medium in both directions. The valve is opened when the maximum permissible pressure is exceeded and it remains wide open during the entire return period, so that the hydraulic medium flows freely at low speed and only slight wear of the valve occurs.

The valve according to the invention is pressed onto its seat by a spring or by compressed air.

Moreover a construction is known, in which three pistons and three cylinders are required, whereby the hydraulic medium is expelled from an intermediate cylinder by two compression pistons, the diameter of which is many times that of the piston in the first cylinder.

In other known arrangements every time the hydraulic safety device has operated the cylinder must be refilled with hydraulic medium. All such arrangements are very inconvenient. The present invention is constructionally much simpler, wear of the parts is reduced and failure cannot occur.

Several embodiments of the invention are illustrated by way of example in the accompanying drawings in which:

Fig. 1 is a vertical section through the tool carrier, the hydraulic safety device, the valve being shown in closed position.

Fig. 2 is a view similar to Fig. 1 showing the valve in the open position.

Figs. 3 and 4 show a positively actuating mechanism for the valve.

Figs. 5 to 8 show the cycle of operations of the positively controlled valve.

Fig. 9 is a vertical section of a modified form of the apparatus wherein the valve is urged to closed position by compressed air.

On a carrier 1 the cutting, pressing or bending tools, not shown in the drawings, are secured. The carrier 1 is actuated by a pressure ram 2 driven by a cam shaft (not shown) and has a lower ball shaped part 3 mounted in a piston 4 and held by a counter plate 5 mounted on said piston. The piston 4 works in a cylinder 6 formed in the tool carrier 1. A space 7 under the piston 4 is filled with fluid and communicates through channels 8 and 9 with an adjoining compartment 10 and a manometer 11 also carried by the tool carrier 1.

A valve 12 is arranged on the side of the tool carrier 1 and the lower end 14 of the spindle 13 of said valve is movable toward and away from one end of an intermediate channel 15 which connects the channels 8 and 9. The valve spindle 13 is acted upon by a spring 16 arranged in the valve casing, the pressure of which spring is adjustable by a cap 17 screwed onto the valve casing. The adjustment depends upon the maximum admissible pressure on the tool carrier 1. The valve spindle 13 passes on the one hand through the valve cap 17 and on the other hand through the valve casing. The valve spindle 13 is screw threaded on its part which projects outside the cap 17, and a head 18 which is screwed on said threaded part is secured in adjusted position by a counter nut 19.

A bracket 20 is arranged on the carrier 1 and carries a bolt 22 urged by a spring 21 toward the head 18. The bolt 22 is prevented from axial rotation by a guide 23. The end of the bolt 22 which is directed towards the valve spindle has a flat portion 24 which engages under the head 18 when the spindle is raised. A notch 24^a formed in the other end of the bolt 22 engages with a corresponding notch 25 in a bolt 26, secured to the pressure ram 2. The end faces of the two notches which face each other are inclined so that they can slide one on the other.

The lifting of the valve spindle 13 is effected by the pressure of the fluid which passes through the channels 8, 15 and 9. The lifting of the valve may however be effected mechanically by the return movement of the pressure ram, as shown in Figs. 3 to 8. In the latter instance the valve is opened if the maximum pressure is not exceeded and consequently if the fluid has not flown over into the adjoining chamber. This is intended to prevent under all circumstances a shortage of fluid in the cylinder chamber of the carrier.

The valve spindle 13 (Fig. 3 and 4) carries on its upper end a head 27 provided with a bearing cavity engaged by a crank 28 carried by one end of a shaft 30, mounted in bracket 29. A lever 31 is carried by the other end of the shaft 30 and has an inclined surface 32 bearing against a roller 33 mounted on a bolt 26 secured to the pressure ram 2. Instead of a spring, compressed air may be used to press the valve onto its seat as shown in Fig. 9. It is easy to calculate the pressure which has to be exerted on the valve in order to obtain the maximum pressure in the hydraulic pressure regulator. The pressure may be easily adjusted on a manometer 11 built in the air conduit.

The compressed air may further be utilized to force back into the cylinder 7 the water, which has flown out from the chamber 7 below the piston into the adjoining chamber 10, and in this manner assist the suction operation of the compression piston 4 on its return stroke. This compressed air in the chamber 10 is under a pressure of 6 to 10 atmospheres whereas a pressure of about 350 atmospheres exists in the chamber 7 when the maximum pressure is exceeded. The slight air pressure in the chamber 10 is insignificant compared with the excess pressure in the compartment below the compression piston.

The use of compressed air presents many advantages. It facilitates the accurate adjustment of the pressure which may act on the valve 14 to open the latter. It also assists the working of compression piston 4 during the suction stroke.

According to Fig. 9 a compression piston, 34 fixed on the valve spindle 13, works in an air cylinder 35. The air cylinder is closed by a screwed-on cover 36 through which the valve spindle 13 extends with suitable packings. The air chamber above the piston 34 permanently communicates with the air feed conduit of an air compressor through an opening α , so that the piston is always under the pressure of the compressed air. The air conduit from the compressor is also connected to the discharge chamber 10 through an orifice 37 so that said chamber is always filled with compressed air from the compressor.

The operation is as follows:

If an undesirable resistance γ (Fig. 2) is offered by the material operated upon to the downward movement of the tool carrier 1 and the maximum working pressure for which the machine is designed is exceeded, the pressure of the piston 4 on the fluid in the cylinder chamber 7 increases until the valve spindle 13 is raised (as the fluid pressure is transmitted through the channel 8 onto the valve 14). The valve spindle 13 held in raised position by engagement of the bolt 22 under the head 18, after the pressure ram 2, has changed its position in relation to the tool holder 1. The fluid then flows from the cylinder 7 through the channels 8, 15, 9 into the adjoining chamber 10. The pressure ram 2 can therefore continue its stroke unimpeded without breakage occurring. After the pressure ram has attained its lowest position and commences its upward movement, it carries along the piston 4 whereby, the pressure in the cylinder chamber 7 is reduced and the fluid is sucked into said chamber from the adjoining chamber 10 through the valve, which is held open by the bolt 22. The valve 13 is closed only when the inclined face of the notch 25 on the bolt 26 rests against the inclined face of the notch 24a on the bolt 22 and the bolt is thereby retracted to release the head 18 of the valve spindle 13 to permit the valve to be moved to closed position under the action of the spring 16. The machine is then ready for the next working stroke (Fig. 1).

The head 18 is so adjusted longitudinally of the valve spindle 13 that the bolt 22 engages said head only when the maximum admissible working pressure on the tool carrier 1 and on the pressure ram 2 is exceeded.

According to Figs. 3 to 8 the pressure ram 2 on its downward stroke moves to the right (Figs. 5 and 6). Thereby the roller 33 on the bolt 26 moves away from the inclined surface of the lever 31. Consequently no movement is transmitted to the valve. After the pressure ram has reached its lowermost position (Fig. 7), the roller 33 comes again into contact with the inclined surface of the lever 31 and presses the lever to one side during the upward stroke of the ram (Fig. 8). Owing to this movement the shaft 30 is rocked and the crank 28 lifts the valve spindle and opens the valve. As the piston 4 is at the same time raised by the pressure ram, fluid will be drawn in through the valve into the cylinder chamber of the carrier. As soon as the pressure ram has attained its uppermost position the valve is again closed.

The surface 32 may be made of such shape that the valve remains wide open until the pressure ram has completed its return stroke.

By the means just described the valve can be caused to open as far as desired so that slow

flowing speeds of the fluid may be obtained and the wear of the valve reduced, the certainty existing that the cylinder chamber 7 of the carrier 1 is always sufficiently filled.

5 When employing compressed air (Fig. 9) the valve is pressed onto its seat by an excess pressure above the air piston 34. On the return stroke of the piston 4 the water forced over into the discharge chamber 10 is forced back into the space 7 under the compression piston 4 on the one hand by the suction action of the piston 4 and on the other hand by the compressed air always present in the chamber 10.

15 I claim:

1. In a press comprising a reciprocating tool carrier and a ram for reciprocating said carrier, means for compensating for excessive resistance offered to the working stroke of said carrier, said means comprising a fluid-containing cylinder formed in said carrier, a piston connected to the ram and working in said cylinder, a chamber carried by said carrier, a conduit connecting said cylinder and chamber, a valve normally closing said conduit and opened by the pressure of the fluid in said cylinder and conduit when such pressure is caused by relative movement of said carrier and ram, during the working stroke 30 of the ram, to exceed a predetermined degree, and means operative during the return stroke of the ram to hold said valve in open position until the ram has completed its working stroke and operable to permit the 35 valve to close as the ram approaches the end of its return stroke.

2. In a press comprising a reciprocating tool carrier and a ram for reciprocating said carrier, means for compensating for excessive resistance offered to the working stroke of said carrier, said means comprising a fluid-containing cylinder formed in said carrier, a piston connected to the ram and working in said cylinder, a chamber carried by said carrier, a conduit connecting said cylinder and chamber, a valve normally closing said conduit and opened by the pressure of fluid in said cylinder and conduit when such pressure is caused by excessive resistance offered 40 to the working stroke of the carrier to exceed a predetermined degree, and spring-actuated means to engage said valve when opened and hold it in open position and means operable at the end of the return stroke of the ram to 45 disengage the last named means from said valve.

3. In a press comprising a reciprocating tool carrier and a ram for reciprocating said carrier, means for compensating for excessive resistance offered to the working stroke of said carrier, said means comprising a fluid-containing cylinder formed in said carrier, a piston connected to the ram and working in said cylinder, a chamber carried by said carrier, a conduit connecting said cylinder

and chamber, a valve normally closing said conduit and opened by the pressure of the fluid in said cylinder and conduit when said pressure due to resistance offered to the working stroke of the carrier exceeds a predetermined degree, a spring pressed bolt engageable with said valve when in open position to hold the valve in such position, and means operative during the return stroke of the ram to retract said bolt.

4. In a press comprising a reciprocating tool carrier and a ram for reciprocating said carrier, means for compensating for excessive resistance offered to the working stroke of said carrier, said means comprising a fluid-containing cylinder formed in said carrier, a piston connected to the ram and working in said cylinder, a chamber carried by said carrier, a conduit connecting said cylinder and chamber, a valve normally closing said conduit and opened by the pressure of fluid in said cylinder and conduit when said pressure is caused by the resistance offered to the working stroke of said carrier to exceed a predetermined degree, said valve having a stem of which the axis is substantially parallel to the axis of said piston, a head longitudinally adjustable on said stem, means automatically engageable with said head when said valve is opened to hold the valve in open position, and means operable by said ram as the ram approaches the end of its return stroke for disengaging said last-named means from said head.

5. In a press comprising a reciprocating tool carrier and a ram for reciprocating said carrier, means for compensating for excessive resistance offered to the working stroke of said carrier, said means comprising a fluid-containing cylinder formed in said carrier, a piston connected to the ram and working in said cylinder, a chamber carried by said carrier, a conduit connecting said cylinder and chamber, a valve normally closing said conduit and having a headed stem, a rockshaft having at one end a crank engaging the head of said stem and at the other end having a lever provided with an inclined surface, and a roller carried by the ram and engageable with said inclined surface during the return stroke of the ram to rock said rock shaft and open said valve.

6. In a press comprising a reciprocating tool carrier and a ram for reciprocating said carrier, means for compensating for excessive resistance offered to the working stroke of said carrier, said means comprising a fluid-containing cylinder formed in said ram, a piston working in said cylinder and connected to said ram, a closed chamber carried by said carrier, a conduit connecting said cylinder and chamber, a closed cylinder carried by said carrier, a piston working in the latter cylinder, a valve carried by one side of the last named piston to intersect and close said

conduit, means for admitting fluid pressure to said closed cylinder above the piston therein for urging said valve to closed position, means operative by said ram during its return stroke to open said valve, and means for admitting fluid pressure to said chamber as said valve is opened to expel the fluid therein back through said conduit to said fluid-containing cylinder when said valve is opened.

10 In testimony whereof I have hereunto set my hand.
